OPERATING LINKAGE FOR HEAVY-DUTY ELECTROMAGNETICALLY OPERATED SWITCHES

Harold E. Schleicher, West Hartford, Conn., assignor to The Arrow-Hart & Hegeman Electric Company, Hartford, Conn., a corporation of Connecticut

Application July 24, 1953, Serial No. 370,131

4 Claims. (Cl. 200—104)

This invention relates to operating linkages for electromagnetically operated switches and particularly those electromagnetically operated switches in which the electromagnet armature moves in a plane parallel to but between a back plate and an insulating base or bases spaced from the back plate, the switch contacts being located on top of the base or bases and operating therethrough. Although the invention relates to and is particularly useful in connection with that type of switch, it is not limited to that use but may be used elsewhere.

Electromagnetically operated switches are commonly provided in different sizes to take care of different current and voltage requirements. For devices designed to handle heavy currents and high voltages the parts are necessarily large because, in order to handle a heavy current, heavy contacts and terminals are required and hence large strong and sturdy supporting mechanism must be provided and operated. Hence the electromagnet also must be larger and more massive. Thus different conditions and circumstances require change in the form and operation of the various types and ratings of electromagnetic switches.

The present invention is particularly adaptable for starting switches and like uses of sizes above 100 H. P. It is desirable in this invention that the movable contact separate from the fixed contacts at a right angle. It is also particularly desirable that there be a sliding motion of the contacts after engagement and before disengagement. This is to clean away oxides and overcome any tendency to weld, which cause difficulties in high current devices. It is also desirable that the operating mechanism function smoothly and with a minimum amount of friction in view of the large size and considerable weight of the parts that must be moved. It is therefore desirable that the operating mechanism employ insofar as possible, pivoted connections between the driving means or electromagnet armature and the movable contact-carrying parts.

Therefore it is an object of the invention to provide improved operating means possessing the aforesaid desirable characteristics for an electromagnetically operated switch or controller in which the movable bridging contacts are mounted on one side of an insulating base and may be moved toward the base into engagement with the fixed contacts and engage at a right angle.

Another object is to provide operating mechanism for switches of the above-mentioned sort in which insofar as compatible with their size and mass the operating parts may be economically manufactured and assembled, and will be of minimum weight commensurate with the necessary strength, and will be reliable during long continued operation.

Other objects and advantages of the invention will become apparent as it is described in connection with the accompanying drawings.

In the drawings—

Fig. 1 is a side elevation view, partly in section and

2

partly broken away, of a switch mechanism embodying the invention.

Fig. 2 is an end elevation view of the invention illustrated in Fig. 1 but with the insulating base and cover elements indicated in phantom.

Fig. 3 is a vertical section view taken along line 3—3 of Fig. 2.

Fig. 4 is a perspective view of the invention illustrated in Figs. 1, 2 and 3, but with the cover, base and contact elements removed.

Referring to the drawings, the invention is shown as applied to a 3-pole electromagnetically operated circuit breaker in which the three sets of movable contacts are each mounted in identical individual insulating housings, 15 each comprising a base 10 and a cover 12 made of molded insulating material. Each base may be of elongated rectangular shape having mounted thereon spaced, aligned, fixed contacts 14', 14" in the shape of rectangular bars or blocks made from heavy gauge sheet metal of good electrical conductivity. Contact buttons 15, 15" of good electrical conductivity are affixed on the inner ends of said bars in position to be engaged by a movable bridging contact 16 such, for example, as is illustrated and described in my Patent No. 2,534,069, issued December 12, 1950. For supporting the insulating bases 10 in parallel arrangement from a metal back or base plate 30 and spaced in front thereof, parallel fabricated side plates 32, 34 are provided adjacent the side edges of the back plate across the top of which transversely extend a 20 pair of spaced parallel heavy sheet metal supporting bars 36, 38. Preferably the fabricated side plates 32 may be formed from a pair of sheet metal plates welded or secured back to back with their upper ends out-turned to afford a broad supporting flange for the bars 36, 38. The lower 25 edges may also be out-turned to lie flat on the back plate 30. Upon the bars 36 and 38 the three insulating bases 10 may be affixed in any suitable manner in position for the three hereinafter-described contact-supporting insulating posts 18 to extend through apertures in 30 the center of said insulating bases.

Each of the bridging contacts 16 is resiliently mounted on a square post 18 of insulating material. A square stud 18a extends from the top of each post and passes through a square hole in the center of the associated 35 bridging contact. Pressing said bridging contact on the top of the post and mounted on the stud 18a is a coiled compression spring 19 with its lower or inner end pressing on the top or outer surface of the contact while its top is engaged and held by a washer 19w fitted in a 40 peripheral slot formed in the top part of the stud.

To move the bridging contact into and out of engagement with the fixed contact the posts 18 are mounted on a contact-carrying bar 20 extending transversely and supported near each end by pairs of closely-spaced parallel legs 22, 22' and 24, 24' (designated, generally, by numerals 22 and 24). These legs may be stamped from sheet metal with upper ends turned at right angles forming flanges below and flush against the under surface of the contact-carrying bar 20.

60 The electromagnet and the actuating means connecting it with the movable contact carrier 20, 22, 24 are located between the bases 10 and the back plate 30 so as to be isolated from the switch contacts and terminals. The electromagnetic operating means may consist of a 65 conventional U-shaped field piece 20 made of laminated magnetic material in the center opening of which is located a conventional solenoid coil 54. Within the coil and movable in and out thereof is a T-shaped armature 54 also made of laminated magnetic material. The field piece is located in parallel relation to the insulating bases and back plate so that the armature will move in 70 a plane parallel to the base and the back plate.

In order to transmit the force of the armature and also to translate its motion from parallel to the bases into motion of the contact to and from the bases, a driving member 55 stamped from sheet metal is loosely and pivotally secured to the armature and is looped around a drive rod 56 extending transversely between the side plates 32 and 34 parallel to the planes of the bases and back plate. The ends of said drive rod are pivotally mounted in an upper corner of a triangular bell-crank driving levers 40, 40' each of which has a pivot bearing mounted in a lower corner by which the bell crank levers are coaxially pivotally mounted on a fixed rod 58 extending transversely between the side plates 32 and 34 near their bottom edges.

The motion of the bell-crank levers 40, 40' is transmitted to the contact carrier by coaxial roller bearing pivotal connections of the lower inner corner of the levers 40, 40' to the lower ends of legs 22, 22', 24, 24' of the contact carrier, the pivot pins 44 and 44' passing through the legs 22, 22' and 24, 24' respectively and the inner corners of the bell-crank lying between the legs 22, 22' and 24, 24' respectively.

In order to guide the upper ends of the carrier legs 22, 24, guide levers 23, 23' extend between legs 22, 22' and 24, 24' respectively and are pivotally connected thereto by coaxial pivot pins 26, 26', respectively, passing therethrough near the tops of said legs.

The guide levers 23, 23' are also pivoted about a fixed pivot rod 25 extending transversely between the side supporting plates 32, 34 and located in the area between the side supporting plates 32, 34 and located in the area between the legs of the contact carrier and one end of the side plates 32, 34 at about the same height as the pins 26, 26'. An extension of each lever 23, 23' has a hooked end over which is looped one end of a coiled tension spring 28, the other ends of said pair of coil springs being hooked around coaxial anchor pins 29, 29' fixedly mounted in the lower part of the side plates 32, 34, respectively.

The springs urge the contact carrier and bridging contacts into open circuit position.

From the foregoing it will be seen that attraction of the armature 54 will cause movement of the drive rod 56 and pivoting of the bell-crank levers 40, 40' about their fixed axis 58 in counter-clockwise direction, referring to Figs. 1 and 3. Such movement causes the pins 44, 44' to move toward the backplate 30 with the contact carrier (18, 20, 22, 24). The axes 58 and 25 are so located with respect to each other and to the pivotal connections of the drive levers 44, 44' and the guide levers 23, 23' that at the instant of engagement of the bridging contact with the fixed contacts the pivots 26, 26' will be in alignment with a line perpendicular to the plane containing the points of engagement of said contacts (see dotted position Fig. 3). Since such line is determined by the position of the contacts and carrier legs at the instant of engagement it is possible then to locate the fixed axes of the drive and guide levers, bearing in mind the desired position of armature at that moment.

The armature will have completed most of its travel so that final movement thereof will merely compress the contact springs 19 to resiliently hold the bridging contact in engagement with the fixed contacts. Since the pivots 26, 44 move in arcs, there will be a slight rubbing motion of the contacts after they engage and before they disengage.

Due to the fixed pivots 25, 28 being on the same side of the contact carrier legs 22, 22' and to the radii about which movable pivots 44 and 26 move not being greatly different, and also to the angles through which drive and guide levers move being small (around 30°), the contact carrier legs remain substantially perpendicular to the aforesaid plane during their entire movement.

Although the fixed contact sets are shown as mounted on separate bases they may also be mounted on a single base.

In the larger sizes of electromagnets it is particularly desirable to reduce power losses, and hence to keep the size of the magnet structure to a minimum commensurate with the power needed to move the switch parts. It is also necessary to hold the laminations of the field piece (whether U-shaped or C-shaped) rigidly in order to prevent loss and to reduce hum. Heretofore iron or steel plates have usually been provided on top and bottom of the stack of laminations extending across the gap between the legs and often of open-centered rectangular shape. These plates were held on top and bottom of the field piece by rivets passing through the whole. I have found that the presence of the metal across the gap reduced the effective power or, in other words, requires a larger magnet structure. By bridging the gap above and below the open ends of the field piece with heavy insulation blocks 60, 62 which are riveted in place by rivets passing through the field piece, a smaller magnet structure is needed and the power delivered is approximately 35% greater.

Modifications within the scope of the invention will occur to those skilled in the art and therefore the invention is not limited to the specific embodiment illustrated.

What I claim is:

1. In combination, an insulating base, fixed contact means mounted thereon, bridging contact means moving to engage and disengage said fixed contacts, and mechanism for transmitting a contact moving force to said bridging contact means to cause perpendicular engagement of the fixed contacts by the bridging contact means comprising contact supporting means having parallel arms extending perpendicularly from said base, a plurality of lever means pivotally connected non-coaxially to said supporting arms at spaced points which are different distances from said base, fixed pivotal mountings for said lever means located at spaced points to cause said lever means both to turn in the same direction when an operating force is applied to one, one of said lever means having its fixed pivotal mounting further from said arm than the other thus to provide said one with a longer lever arm than said other, whereby said mechanism moves the bridging contact means into engagement with the fixed contact means perpendicularly.

2. In an electric switch, the combination claimed in claim 1 wherein one lever means is in the form of a bell-crank, and operating means connected thereto movable in a direction substantially perpendicular to the movement of said contact supporting means.

3. In an electric switch, the combination claimed in claim 2 wherein the bridging contact means are mounted on an insulating support carried by the contact supporting means, said support having portions extending through said base on which said bridging contact means are mounted, said mechanism for moving said bridging contact means being on the opposite side of the base.

4. In an electric switch, the combination claimed in claim 2 wherein the bell-crank lever means is farther from the bridging contact means than is said other lever and is the shorter of said two lever arms.
